US00D810775S

(12) **United States Design Patent** (10) **Patent No.:** **US D810,775 S**
(45) **Date of Patent:** **** Feb. 20, 2018**

(54) **COMPUTER DISPLAY PANEL WITH A GRAPHICAL LIVE ELECTRONIC THREAT INTELLIGENCE VISUALIZATION INTERFACE**

(71) Applicant: **NORSE NETWORKS, INC.**, St. Louis, MO (US)

(72) Inventor: **Tommy Stiansen**, Hillsborough, CA (US)

(73) Assignee: **NORSE NETWORKS, INC.**, St. Louis, MO (US)

(**) Term: **15 Years**

(21) Appl. No.: **29/600,740**

(22) Filed: **Apr. 14, 2017**

Related U.S. Application Data

(63) Continuation-in-part of application No. 29/524,595, filed on Apr. 21, 2015, now abandoned.

(51) **LOC (11) Cl. 14-04**

(52) **U.S. Cl.**

USPC **D14/486**

(57) **CLAIM**

The ornamental design for an computer display panel with a graphical live electronic threat intelligence visualization interface, as shown and described.

DESCRIPTION

The FIGURE is a front view of a computer display panel with a graphical live electronic threat intelligence visualization interface, showing my new design.

The broken lines in the drawing represent portions of the computer display panel that form no part of the claimed design.
